PILOT BURNER

Stanley S. Guelson, Milwaukee, Wis., assignor to
 Milwaukee Gas Specialty Company, Milwaukee,
 Wis., a corporation of Wisconsin

Application February 19, 1942, Serial No. 431,489

4 Claims. (Cl. 158—99)

This invention relates to burner apparatus and has particular reference to an improved form of pilot burner for maintaining a pilot flame in position to light a main burner when the gas or other fuel supply for the main burner is turned on.

More particularly, the present invention has to do with a Bunsen type of pilot burner, and still more particularly with a pilot burner provided with a mounting bracket and support for a thermosensitive element responsive to the heat of the pilot flame and operable in conjunction with control means to maintain the supply of fuel for the main burner as long as the pilot flame is burning and to shut off the supply of fuel for the main burner upon extinguishment of the pilot flame.

It is to be understood that the invention, in its broader aspects, is not limited to the particular use herein disclosed, nor to use of a thermosensitive element with the pilot burner, but may be employed for all similar or equivalent purposes and, in its broader aspects, with or without the thermosensitive element.

Heretofore, pilot burners of the class described, and particularly the pilot burner bodies, have usually been cast to form. The metals suitable for making cast burners of this sort are not now readily available due to war priorities.

One of the main objects of the present invention is to provide a pilot burner of simple, relatively inexpensive, and improved construction, and, more particularly, an improved pilot burner construction which will enable, by the use of stampings stamped from flat sheet metal stock, fabrication of the pilot burner body with all of the features of a cast and machined pilot burner body.

Another and more specific object of the invention is to provide an improved pilot burner body comprising a pair of sheet metal stampings which, when assembled and joined together, form the venturi, mixing chamber and primary air holes of a Bunsen type pilot burner; also a pilot burner body of the class described in which the stampings, when assembled and joined together, permit the inlet fitting or spud and the pilot burner tip to be inserted and secured in the body of the pilot burner in a simple and expeditious manner.

Another and more specific object of the invention is to provide an improved mounting bracket for the pilot burner, which mounting bracket is also formed of a stamping stamped from flat sheet metal stock, and, more particularly, a mounting bracket of the class described which is also adapted to support the thermosensitive element in position where it is responsive to the heat of the pilot flame.

Further objects and advantages of the inven-

tion will be apparent from the following detailed description, taken in connection with the accompanying drawings in which:

Figure 1 is a side elevational view of a pilot burner embodying the present invention;

Figure 2 is a front elevational view of the pilot burner taken at substantially right angles to Figure 1;

Figure 3 is a top plan view of the pilot burner and mounting bracket as shown in Figure 1;

Figure 4 is a bottom plan view of the pilot burner and mounting bracket as shown in Figure 2;

Figure 5 is a transverse section taken on the line 5—5 of Figure 2;

Figure 6 is a transverse section taken on the line 6—6 of Figure 2;

Figure 7 is an exploded view showing in longitudinal section the pilot burner tip, the mounting bracket, the pilot burner body, and the inlet fitting washer, and, in elevation, the inlet fitting or spud;

Figure 8 is a top plan view of the mounting bracket shown in Figures 1 to 4, inclusive, and in Figure 7;

Figure 9 is a top plan view showing another form of mounting bracket with the body of the pilot burner in transverse section;

Figure 10 is a bottom plan view similar to Figure 9 showing a further form of mounting bracket for the pilot burner; and

Figure 11 is a fragmentary view of the inlet and of the pilot burner body showing the primary air openings formed by slitting or piercing the sides of the body and stamping or pressing the stampings out in the manner shown.

Referring to the drawings, the pilot burner selected for illustration comprises the main pilot burner body 10 having at one end the inlet fitting or spud 11 for supplying gas or other fuel to the pilot burner.

The opposite end of the pilot burner body 10 is provided with the pilot burner tip 12 drilled and ported at 13 to provide an ignition flame for lighting the main burner when the gas or other fuel supply therefor is turned on. The drilling and porting of the pilot burner tip 12 at 13 may be as shown in the drawings, or of any other desired form, many variations of the particular drilling and porting of the pilot burner tip at 12 being well known in the art. Where a thermoelectric generator (shown in the form of a thermocouple) or other thermosensitive element is used with the pilot burner as shown and described,

the drilling and porting of the pilot burner tip also maintains a flame for heating the "hot" junction or junctions of the thermosensitive element.

The burner body 10 comprises a pair of stampings 15 and 16 formed of any flat sheet metal stock of suitable gauge, such as brass, steel, stain-

less steel or the like. The stampings 15 and 16, which are blanked out to provide the formation shown and described, are stamped to form complementary channels 17 and 18 for forming, when assembled, a fuel supply passage. The channels 17 and 18 are of relatively restricted form intermediate the ends of the burner body to form a Venturi portion indicated in general at 19. The channels 17 and 18 are stamped to give the passage defined by the stampings 15 and 16 enlarged form at one end of the burner body 10 at 20, and generally enlarged form at the opposite end of the burner body 10 at 21.

Flanges 22 and 23 extend marginally along opposite sides of the stamping 15. The other stamping 16 has flanges 24 and 25 extending marginally along opposite sides thereof and crimped over the flanges 22 and 23 to join the stampings 15 and 16 together and to close, at opposite sides of the burner body, the longitudinal passage defined by the stampings 15 and 16. The extended flanges of the stampings 15 and 16 may be welded together, instead of crimped, or they may be otherwise joined within the broader aspects of the invention.

The pilot burner tip 12 has a reduced integral neck 28 which fits telescopically in the enlarged end 20 of the longitudinal passage defined by the stampings 15 and 16. The pilot tip 12 may be secured in the end of the burner body, for example by pressed fit, or by inserting a pin, or pins, 30 (Figure 2) in an opening, or openings, 31 (Figure 7) in the burner body and into an opening or openings 32 in the reduced neck 28 of the pilot tip upon inserting the neck of the pilot tip into the burner body, or by crimping the pilot tip surrounding portion of the burner body into a groove in the pilot tip, or in any other suitable manner. Alternatively, for example, the pilot burner tip may fit the outside of the burner body or it may be joined to the burner body in any other suitable manner.

The inlet fitting or spud 11 for the delivery of gas or other fuel to the interior of the pilot burner body 10 is inserted or fitted into the opposite enlarged end 21 of the longitudinal passage formed by the complementary enlarged portions of the channels 17 and 18. The mounting of the inlet fitting 11 in the burner body 10 may be accomplished by various means. In the illustrated embodiment of the invention, a washer 36 is secured, for example, by pressed fit between the stampings 15 and 16 with the integral radial flange 38 of the washer abutting the adjacent end of the burner body.

The washer 36 is of the extruded type and is internally threaded at 39 to permit the threaded portion 40 of the spud 11 to be screwed into place in the washer 36 with the fuel outlet orifice 41 of the spud directed into the adjacent enlarged end of the passage defined between the stampings 15 and 16. It is also possible to tap the stampings 15 and 16, after they are joined together, along the portion into which the spud 11 is inserted and to screw the spud 11 directly into the pilot burner body 10. The spud 11 is shown provided with a polygonal or other suitably formed portion 42 adapted to be engaged by a suitable tool for screwing the spud into place and for removing it from the burner body. The outer end of the spud 11 is threaded at 43 for threaded engagement, for example, with a coupling nut 44 for joining the pilot fuel supply pipe 45 to the spud 11 so that the fuel from the pipe or tube 45

will enter the pilot burner body 10 through the spud orifice 41.

Diametrically opposite supplementary channels 50 and 51 are stamped in the walls of the stampings 15 and 16 adjacent the enlarged end 21 of the longitudinal passage. In Figures 1, 2, 4, 6, and 7 these channels 50 and 51 open endwise from the pilot burner body 10 laterally of the flange 38 of the washer 36 to form primary air admission ports 52 and 53 as shown in Figure 4 for the admission of primary air into the mixing chamber formed by the enlarged end 21 of the longitudinal passage. The mixture of gas and air passes outwardly through the Venturi portion 19 of the passage and into the hollow interior or longitudinal passage 54 in the pilot tip 12, from where it issues through the drilled and ported outlet 13 to maintain, when ignited, the pilot flame for igniting the main burner and for heating the thermosensitive element. The flange 38 of the washer 36 is used to control the size of the primary air admission ports 52 and 53, the diameter of the flange controlling the size of these ports.

In the modification shown fragmentarily in Figure 11, the inlet ends of the stampings 15, 16' are slit or pierced at 90 and the primary air openings 51 are formed by stamping or pressing the stampings out, as at 92.

A mounting bracket 58, also formed of sheet metal stock, is stamped to form and provided with an opening 59 which conforms, in general, with and fits over the external cross-sectional contour of the inner end of the upper enlarged portion of the burner body 10 and the joined side flanges thereof. The mounting bracket 58 has a marginal flange 60 which extends in a direction generally longitudinally of the burner body, and is crimped, for example, at 62 upon the complementary and joined flanges 22, 24, and 23, 25 for securing the mounting bracket in place upon the burner body. The mounting bracket 58 may be secured in place upon the burner body by other means within the broader aspects of the present invention. The mounting bracket may be provided with protruding tangs 59a disposed adjacent the crimped or joined flanges of the pilot body and welded thereto for locating the bracket with respect to the body.

Where a thermosensitive element is employed in combination with the pilot burner, the mounting bracket 58 is provided with a second opening 64, and the thermosensitive element, which is illustrated in the form of a thermocouple 65, is mounted in this second opening 64 in position to be heated by the pilot flame.

The form of the thermocouple and lead connection therefor may vary widely within the scope of the present invention. The particular thermocouple and lead connection selected for illustration are of the general character disclosed and claimed in Oscar J. Leins Patent No. 2,126,564, granted August 9, 1938. The thermocouple 65 comprises an outer tubular metallic thermocouple member 66 and an inner metallic thermocouple member 67 disposed within the outer thermocouple member and joined at one end to the outer end of the outer thermocouple member to form the thermojunction 68 which is positioned to be heated by the pilot flame. An inner lead conductor 69 is joined to the inner thermocouple member 67 to form an internal thermojunction 70, and an outer tubular lead conductor 71 surrounds the inner lead conductor 69 and is connected, for example, through a sleeve

72 to the outer thermocouple member 66 to form a third thermojunction 73. The inner lead conductor 69 is insulated from the outer lead conductor 71 by a wrapping of insulation 74 on the inner lead conductor, the lead conductors preferably having sufficient flexibility to permit them to be extended and connected to the thermoelectric safety shutoff device for the main burner as suitable or desired.

The thermocouple 65 may be detachably fastened in place in the opening 64 in the mounting bracket 58 by various means. In the illustrated embodiment of the invention, the thermocouple 65 and the adjacent end of the sleeve 72 are adapted to be passed through the opening 64. The sleeve 72 has an integral annular flange 76 which abuts the mounting bracket 58 as shown. The sleeve 72, outwardly of the flange 76, is threaded at 78 for threaded engagement with a nut 79 for detachably clamping the thermocouple in place on the bracket 58. Of course the thermocouple and leads therefor may be of existing form and provided with means for detachably securing the same to the mounting bracket 58 without requiring a flange 76 and threads 78 on the sleeve 72 of the thermocouple, as shown and described. If desired, the opening 64 may be threaded and the sleeve 72 may be threaded directly into the threaded opening 64.

The bracket 58 has an integral flange 80 provided with openings 81 through which the bracket is detachably or otherwise secured, for example, by bolts and nuts 82 or other fastening means, to the main burner or other support indicated fragmentarily at 83.

In the embodiment of the invention shown in Figures 1 to 8, inclusive, the openings 69 and 64 in the mounting bracket 58 are shown spaced in a direction at substantially right angles to the flange 80. Various other designs of these mounting brackets are contemplated within the scope of the present invention.

I shall not show all possible variations in the design of the mounting bracket, but to illustrate some variations I have shown in Figure 9 the openings 69a and 64a as spaced in a direction generally parallel to the mounting flange 80a, and in Figure 10 I have illustrated a further modification in which the outer periphery of the mounting flange 80b of the bracket 58b is of generally circular form and provided with a peripheral flange at 85 and with mounting openings 86 shown positioned diametrically opposite each other. Various other forms of mounting may be provided, and it is to be understood that various forms of porting and drilling of the pilot burner tip 12 at 13 are contemplated within the scope of the present invention.

I do not intend to be limited to the precise details shown or described.

I claim:

1. As a new article of manufacture, a burner comprising a burner body composed of a pair of stampings formed of sheet metal stock stamped to form complementary channels for forming, when assembled, a fuel supply passage between said stampings, said channels being of relatively restricted form intermediate the opposite ends of the burner body to form a Venturi portion, flanges extending marginally along opposite sides of one of said stampings, flanges extending mar-

ginally along opposite sides of the other stamping and crimped over said first mentioned flanges to close said passage at opposite sides of the burner body and to join said stampings together, and a mounting bracket formed of sheet metal stock stamped to form and provided with an opening fitting over the external cross-sectional contour of the burner body, said mounting bracket having a marginal flange extending generally longitudinally of the burner body and crimped upon the complementary portions of the burner body for securing the mounting bracket to the burner body.

2. As a new article of manufacture, a burner comprising a burner body composed of a pair of stampings formed of sheet metal stock stamped to form complementary channels for forming, when assembled, a fuel supply passage between said stampings, said channels being of relatively restricted form intermediate the opposite ends of the burner body to form a Venturi portion, flanges extending marginally along opposite sides of one of said stampings, flanges extending marginally along opposite sides of the other stamping and crimped over said first mentioned flanges to close said passage at opposite sides of the burner body and to join said stampings together, said channels being stamped to give the passage relatively enlarged form at each of the opposite ends of the burner body, a fuel inlet fitting mounted in the enlarged end of said passage at one end of the burner body, a pilot burner tip mounted in the enlarged end of the passage at the other end of the burner body, supplementary channels stamped in the walls of the enlarged end of said passage forming channels adjacent said inlet fitting and opening laterally of said fitting to form primary air admission ports for the admission of primary air to said burner body, and a mounting bracket formed of sheet metal stock stamped to form and provided with an opening fitting over the external cross-sectional contour of the burner body, said mounting bracket having a marginal flange extending generally longitudinally of the burner body and crimped upon the complementary portions of the burner body for securing the mounting bracket to the burner body.

3. As a new article of manufacture, a burner comprising a sheet metal body defining a fuel supply passage restricted between its ends to form a Venturi portion, said body being provided at opposite sides thereof with lengthwise outwardly projecting exterior flanges, and a sheet metal mounting bracket having an opening fitting about said body and said flanges thereof, said mounting bracket having a marginal flange extending generally lengthwise of said burner body and crimped upon said body flanges securing said bracket to said burner body.

4. As a new article of manufacture, a burner comprising a sheet metal body provided with lengthwise outwardly projecting exterior flanges, and a sheet metal mounting bracket having an opening fitting about said body and said flanges thereof, said bracket having flange elements extending generally lengthwise of said burner body disposed at opposite sides of and crimped upon said body flanges securing said bracket to said burner body.

STANLEY S. GUELSON.
